UNITED STATES PATENT OFFICE.

ROBERT CARL RAHM, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

BRAIDING MECHANISM.

1,182,036.

Specification of Letters Patent.

Patented May 9, 1916.

Application filed January 22, 1915. Serial No. 3,711.

To all whom it may concern:

Be it known that I, ROBERT CARL RAHM, a citizen of the United States, residing at Wyomissing, in the county of Berks and State of Pennsylvania, have invented certain new and useful Improvements in Braiding Mechanism, of which the following is a specification.

My invention relates to braiding machines, and it consists particularly in improved means for controlling the bobbins during their serpentine braiding movement so as to prevent the twisting action which ordinarily results from such movement. This well known twisting action is the natural result of the ordinary movement of the carriers in their race-circle course, each carrier making a complete turn upon its own axis in rounding a terminal, as will be readily understood.

My special object is to provide for uniformly presenting the same surface portions of the bobbin strands or yarns upon a determined face of the braid fabric produced, and to this end my invention consists in providing means for practically preventing axial turning movement of the carrier as fully described in connection with the accompanying drawings and particularly pointed out in the claims.

Figure 1 is a plan view of a short-race-way braider having my invention applied thereto in preferred manner; parts thereof being removed to more clearly reveal the construction. Fig. 2 is a similar partly sectional side elevation, and Fig. 3 is a partial end view thereof. Fig. 4 shows a braid section illustrating the effect produced; the lay of three separate strands employed upon each carrier being indicated in this particular product.

The drive gears of the construction illustrated, are mounted as usual upon studs or posts 2 fixed to the bottom plate, with quoits 3 fixed to these studs at their upper ends, in the plane of the top plate 4, so as to form the intersecting race circles of the serpentine raceway in which the bobbin carriers travel. Each of these drive gears comprises the usual intermeshing toothed wheel 10, and horn wheel 11; the latter being shown as provided with three carrier-engaging horns or notches for the terminal gears, and with four for the intermediate gears. In my improved construction illustrated each

of these drive gears is suitably provided in addition, with a series of radiating arms 12, corresponding in number with the horns provided in the horn wheel 11 thereof, each of which arms is provided at its outer end with a pivotally mounted carrier guide 13.

The bobbin carriers comprise as usual, a base portion adapted to travel in the serpentine raceway of the top plate and to be operatively engaged by the horn wheels of the successive drive gears. In my improved construction, however, the raceway-engaging portion thereof is formed as a separate shuttle piece 15, having plate-engaging collars 17 and 18 and a horn-engaging portion 19 as indicated. This shuttle piece is rotatably mounted upon the carrier spindle 16, which is rigidly fixed to the body 21 of the carrier, so as to permit said shuttle piece to freely adjust itself to the curves of the race-way without correspondingly turning the body of the carrier. The depending spindle stud 16 of the latter is formed with a T-head 20 adapted to engage the pivotally mounted carrier guides 13 of the successive drive gears, so as to permit control of the carriers as to axial turning movement, independently of the shuttle piece 15. This control of the carriers as to turning movement upon their own axes, is such as to prevent twisting action by holding them substantially square to the center line $x-x$ extending through the drive gear studs, at all points of their travel through the curved raceway around said studs. This is effected, as shown, by means of eccentrically arranged connecting rings 25, each of which is connected to the series of pivotally mounted carrier guides 13 of a drive gear, by a corresponding series of links 26, so as to hold all of said guides in parallel relation as they are rotated with the ring by the drive gear; suitably located guide rollers 27, 27 being provided to retain the floating ring 25 in the determined eccentric path of rotation around the drive gear center whereby the desired effect is produced. The head of each pivotally mounted guide 13 is provided with a guide groove 28 which receives and engages the T-head 20 of each passing carrier and retains it at all times in parallel relation with the T-heads of the other carriers.

Any desired number of bobbins may be mounted upon each of a desired series of carriers, and the number of drive gears em-

ployed may vary from a minimum of two terminal gears as employed in soutache braiding. In each case the carriers may be traversed around the endless serpentine course practically without turning them upon their own axes as occurs when the race-way-engaging shuttle piece is a rigid part thereof, so that the braiding strand or strands will be uniformly laid without twisting effect and so as to present the same surface portions thereof upon a determined face of the fabric, as indicated in Fig. 4. If a single flat-faced strand is employed, of square cross-section for instance, it will not be twisted at the edges of the fabric but uniformly present the same faces. The specific construction set forth may obviously be modified without departing from the invention.

What I claim is:

- 20 1. A braiding machine comprising a serpentine raceway, a series of bobbin carriers each provided with a rotatably mounted shuttle-piece, drive gears therefor, and controlling connections between said carriers and drive gears whereby twisting axial movement of the driven carriers is prevented.
- 25 2. A braiding machine comprising a serpentine raceway, a series of bobbin carriers, each provided with a rotatably mounted shuttle-piece, drive gears therefor each provided with a series of pivotally mounted carrier guides, and means for maintaining said guides in parallel relation during rotation of the gears.
- 30 3. A braiding machine comprising a serpentine raceway, a series of bobbin carriers each provided with a rotatably mounted shuttle-piece and a fixed guide-head, drive gears therefor each provided with a series of pivotally mounted carrier guides, and

means for maintaining said guides in parallel relation during rotation of the gears.

4. A braiding machine comprising a serpentine raceway, a series of bobbin carriers each provided with a rotatably mounted shuttle-piece, drive gears therefor each provided with a series of pivotally mounted carrier guides, and an eccentrically arranged rotary ring linked to said pivotally mounted carrier guides. 45

5. A braiding machine comprising a serpentine raceway, a series of bobbin carriers each provided with a rotatably mounted shuttle-piece, drive gears therefor each provided with a series of pivotally mounted carrier guides, an eccentrically arranged rotary ring linked to said pivotally mounted carrier guides, and relatively - fixed guides for said ring. 55

6. A braiding machine comprising a serpentine race-way, a series of bobbin carriers each provided with a depending guide head, drive gears therefor each provided with a series of pivotally mounted carrier guides engaging said heads, and means for maintaining said guides in parallel relation during rotation of the gears. 65

7. A braiding machine comprising a serpentine race-way, a series of bobbin carriers each provided with a depending guide head, drive gears therefor each provided with a series of pivotally mounted carrier guides engaging said heads, and an eccentrically arranged rotary ring linked to said pivotally mounted carrier guides. 70 75

In testimony whereof I affix my signature in presence of two witnesses.

ROBERT CARL RAHM.
